(57) CLAIM

The ornamental design for an ornamental choker with bra extension, as shown and described.

DESCRIPTION

FIG. 1 is a perspective view of an ornamental choker with bra extension, showing my new design;

FIG. 2 is a top plan view thereof;

FIG. 3 is a front view thereof;

FIG. 4 is a back view thereof;

FIG. 5 is a left side view thereof;

FIG. 6 is a right side view thereof;

FIG. 7 is a bottom view thereof; and,

FIG. 8 is a perspective view of my design of FIG. 1 shown in place on a human torso.

The human torso depicted in FIG. 8 has been shown for illustrative environmental purposes only and forms no part of the claimed design.

The broken line showing of the human form in FIG. 8 is for illustrative purposes only and forms no part of the claimed design.
